MEANS FOR APPLYING SILICATE TO CORRUGATED STRAWPAPER

Filed Oct. 11, 1923

Inventor

Charles Everett Colgrove.
By E. F. Etherston Haugh.

Attorney

UNITED STATES PATENT OFFICE.

CHARLES EVERETT COLGROVE, OF TORONTO, ONTARIO, CANADA.

MEANS FOR APPLYING SILICATE TO CORRUGATED STRAWPAPER.

Application filed October 11, 1923. Serial No. 667,887.

To all whom it may concern:

Be it known that I, CHARLES EVERETT COLGROVE, a subject of the King of Great Britain, residing at No. 142 Delaware Ave., in the city of Toronto, in the county of York, in the Province of Ontario, in the Dominion of Canada, have invented a new and useful Improvement in Means for Applying Silicate to Corrugated Strawpaper, 10 of which the following is a specification.

"Statement of invention."

This invention relates to improvements in means for applying silicate to corrugated straw-paper, and to corrugated paper board manufacturing means generally, as described in the present specification and shown in the accompanying drawings.

The invention consists essentially of the 20 novel features pointed out broadly and specifically in the claim for novelty following a description in detail of an acceptable form of the invention.

To facilitate a thorough comprehension 25 of my invention, I shall refer briefly to the prior art, in which the usual silicate rolls pick up the silicate from the silicate pan and apply a thin film thereof upon a transfer roll, which applies the same to the tips 30 of the corrugated straw-paper as it is fed from the corrugating machine.

Any adhesive in excess of the quantity 35 necessary to form a bond along the line of contact of the tips of the corrugated straw-paper and the liner is a waste, and to obviate this the tips of the corrugation are directed downwardly when the silicate is applied, so that the adhesive will tend to flow towards, rather than away from the 40 line of contact.

In some machines the first liner is applied while the straw-paper is still on one of the corrugated rolls, or the liner may be brought up into contact with the corrugated straw-paper and the two together pass over a platform which dries it and sets the silicate. In such mechanisms the single faced web must be turned back over the machine and passed through a second unit of machines to invert the web so that the ordinary straw-paper may be permanently secured to the corrugated straw-paper, thus forming a smooth surface.

The objects of my invention are, with the foregoing in view, to provide means for ap-

plying the silicate to the tips of the corrugations while the same are directed upwardly in such quantities as are required to effect the proper bond between the corrugated straw-board and the liner; and for 60 obviating the possibilities of applying an excess of silicate to the tips of the corrugations; to provide means whereby the silicate may be applied to the straw-paper as the same is fed in a horizontal plane from the corrugator, thereby obviating the necessity of employing additional mechanisms for carrying the web back over the corrugator and inverting it for the purpose described; to bring about a churning action 70 of the silicate to promote its adhesive qualities; to provide means for adjusting the relation of the instrumentalities constituting such a mechanism so that the amount of silicate applied to the straw-paper may be regulated in accordance with the specific requirements; and generally to provide a structure with a view to compactness and durability, wherein the number of parts are few, the construction simple, 80 and the cost of maintenance low.

The drawing is a fragmentary sectional elevation illustrating the association of the instrumentalities constituting my invention.

"General construction."

My invention may be built into a corrugating machine or may be used as an independent unit in advance of the corrugator to receive the web as it is fed therefrom. 90 In the drawing I have illustrated relation of the instrumentalities constituting my invention, it being understood that the same extend transversally of the machine parallel with the corrugations of the straw-paper.

The term "silicate pan" as used herein, is intended to include a pan, vat or any equivalent means for containing a quantity of silicate of soda. A very brief description 100 of the silicate pan to which the attachment of this invention is applied will suffice, since the particular type of such pan is immaterial to the invention which has a wide range of applicability to various kinds 105 of machines, irrespective of the specific form of the said silicate pan, per se.

In the drawing is illustrated silicate pan 1 of any desired formation, to the ends of which are connected the castings 2 and 3. 110

Said castings are perforated as at 4 to receive extremities of the spindle or shaft 5 which serves to carry the pick-up roll 6. For the purpose of illustration, the said roll 5 may be driven from overhead line shaft through the medium of the belt 7 trained over the pulley wheel 8 mounted upon the spindle 5.

The numerals 9 and 10 designate the intermediate and transfer rolls respectively which are carried upon spindles 11 and 12 journaled in adjustable bearings 13 carried upon the end castings 2 and 3. The intermediate roll 9 is rotated incidental to the intermeshing of the pinion 14 carried upon the spindle 11 and the spur gear 15 positioned on the spindle 5, and its rotating action is transmitted to the transfer roll 10 incidental to the intermeshing of the pinion 14 and the pinion 16 carried upon the spindle 12. The adjustable journals as illustrated provide means for adjusting the intermediate rolls, and the transfer roll in relation to the web of corrugated straw-board which is fed therebeneath as illustrated, and indicated in its entirety by the numerals 19.

"General operation."

The pick-up roll 6 serves to pick up the silicate contained in the silicate pan 1, as is conventionally illustrated, and transfer it to the surface of the intermediate roll 9 which is spaced in relation thereto just sufficiently to accommodate for a very thin film of silicate according to the existing requirements. The intermediate roll 9 serves to transfer the film of silicate obtained from the pick-up roll 6 to the transfer roll 10, which is also spaced in relation to the intermediate roll 9 to permit the transfer of the required film of silicate. The rotating transfer roll 10 applies the film of silicate upon the tips 18 of the corrugated straw-paper 19; and the straw-paper and the web 45 is advanced to receive the upper or second liner.

The travel of the silicate about the intermediate and transfer rolls serves to bring about a churning action of the silicate to produce the desired adhesive qualities. The employment of the intermediate roll obliterates the possibility of applying excessive silicate to the tips of the corrugations, due to the fact that any surplus silicate which 55 may have fed from the pick-up roll to the intermediate roll and to the transfer roll,

will be returned to the transfer roll and to the pick-up roll, as is described.

Assuming that the pick-up roll is rotating in the direction of the indicating arrow A, the film of silicate pick-up will be applied at the point of contact B, the intermediate roll rotating in the direction of the indicating arrow C. The film of silicate is transferred from the intermediate roll 9 to the transfer roll 10 at the point of contact D, the transfer roll rotating in the direction of the indicating arrow E. The film of silicate is applied to the tips 18 of the corrugations 19 at the position indicated by F; and any excessive film adhering to the roll will be carried back to the location indicated by D and transferred to the intermediate roll 9, which will serve to convey the same back to the pick-up roll 6 and to the silicate pan 1.

It is obvious that the introduction of the intermediate roll 9 not only serves to effect a churning action to promote the adhesiveness of the silicate but to provide means for applying the required amount of silicate to the tips of the straw-paper in the manner illustrated, which obviates the necessity of employing considerable collateral mechanism and factory space to accommodate for same.

A perusal of the preceding elucidation is deemed sufficient to enable one skilled in the art to readily comprehend the novelty and desirability of my invention, and that deviations from such detail in its precise formation and association of parts may be resorted to without forming a departure from the spirit of the invention and the scope of the appended claim.

What I claim is:

In means for applying silicate to corrugated straw-paper comprising a driver dipping roller, and a tank containing the silicate, an intermediate roller receiving its silicate in contact with said dipping roller, an application and feed roller below said intermediate roller receiving its silicate in contact with the latter, gears rigidly secured to said rollers and intermeshing one with the other, and means providing a path through the machine under said feed and application roller for the passage of the corrugated paper and adapted to permit actuating engagement of the corrugations with the teeth of the gear on said feed roller.

CHARLES EVERETT COLGROVE,
